UNITED STATES PATENT OFFICE.

JOHN J. CHAPIN, OF NEW YORK, N. Y., ASSIGNOR TO REMINGTON ACCOUNTING MACHINE CORPORATION, OF ILION, NEW YORK, A CORPORATION OF NEW YORK.

CALCULATING MACHINE.

Application filed May 16, 1921. Serial No. 469,881.

To all whom it may concern:

Be it known that I, JOHN J. CHAPIN, citizen of the United States, and resident of the borough of Manhattan, city of New York, 5 in the county of New York and State of New York, have invented certain new and useful Improvements in Calculating Machines, of which the following is a specification.

10 My invention relates to calculating machines, and more especially to combined typewriting and calculating machines. My invention has for its principal object to provide certain improvements in the actuating mechanism of key operated machines of the class specified, with a view to simplifying the mechanism and to improving it with respect to lightness of touch on the key and with respect to speed of operation. My invention also includes various detail improvements.

Another object of my invention is to provide actuating mechanism for these machines of such sort that it can be very readily assembled, and that parts thereof can be easily removed and if necessary replaced with new ones or repaired. My actuator is also characterized by the use of very few springs, the action being mostly positive. 30 This feature both results in ease of operation and also makes for reliability.

To the above and other ends which will hereinafter appear, my invention consists in certain features of construction and combinations and arrangements of parts, all of 35 which will be fully set forth herein and particularly pointed out in the claims.

In the accompanying drawings,

Figure 1 is a simplified, or more or less 40 conventional side elevation of a combined typewriting and calculating machine having my invention embodied therein.

Figure 2 is a front elevation of the actuator detached from the remainder of the 45 machine and with some parts broken away and other parts omitted.

Figure 3 is a vertical section with parts 50 broken away, taken through the axis of the main pivot rod.

Figure 4 is a view in vertical section on the line 4—4 of Fig. 2 and showing the parts in normal position.

Figure 5 is a similar view with a key partly depressed, and Figure 6 is a similar

view showing the parts at the end of the 55 down stroke of the key.

Figure 7 is a fragmentary top plan view in section through the key arrestor or single-key tube.

Figures 8 and 9 are vertical sectional 60 views on the line 8—9 of Fig. 2 and looking toward the left. The disconnect mechanism is shown in connecting position in Fig. 8 and in disconnect position in Fig. 9.

Figure 10 is a fragmentary view in vertical section on the line 10—10 of Fig. 2 and looking toward the left and showing the parts during the down stroke of a key.

Figure 11 is a fragmentary view of a portion of the same as seen during the upstroke 70 of a key.

Figure 12 is a fragmentary front elevation, partly in section, of a portion of the mechanism.

Figure 13 is a front view, partly in section, of a certain spring coupling.

Figure 14 is a sectional view on the line 14—14 of Figs. 2 and 12 and looking toward the left, the parts being in normal position.

Figure 15 is a similar view on the line 80 15—15 of Figs. 2 and 12.

Figure 16 is a diagrammatic view showing all of the differential plates as seen from the left-hand end on the pivot rod on which they are mounted and illustrating the means 85 for providing different extents of lost motion.

Figure 17 is a rear view of the differential stop bar detached from the machine.

Figure 18 is a front to rear vertical sectional view illustrating a modification of 90 certain of the devices.

My improved actuating mechanism may be applied in various ways and combined with various other devices, but for the purpose of illustration I have here shown it embodied in a machine which in respects other than my improvements resembles, and in fact may be identical with, the Remington accounting machines that have been on the 100 market for some years and which consist essentially of a Remington No. 11 typewriter having combined therewith the Wahl calculating mechanism. Wherever any parts of the calculating machine are omitted 105 either in the drawings or in the description, it is to be understood that the Remington-Wahl mechanism may be used; and in fact

the specific machine illustrated in the drawings might be considered to be in the nature of a modification of the well-known Remington-Wahl machine. One form of said machine is fully disclosed in the patent to Wahl No. 1,270,471 dated June 25, 1918. The machine shown in that patent, however, includes cross footing mechanism which is not included in the machine shown in my drawings. My improvements are confined to the main actuator mechanism of the machine. The typewriter, the carriage including the calculator truck, and the totalizer or totalizers, are all shown of standard Remington-Wahl construction.

The Remington typewriter includes a main frame 20 having thereon stationary rails 21 constituting parts of ball bearings for a traveling carriage 22 having a platen 23 mounted thereon. The frame also includes a type bar segment 24 having front strike type bars 25 pivoted therein and actuated by links 26, bell cranks 27 and links 28, the last connected to the key levers 30 of a set of numeral keys 31 and alphabet keys 32. This machine also includes various devices well-known in the art and not necessary here to be particularly shown and described. Fig. 1 contains a conventional representation of this machine.

The calculating mechanism comprises a stationary frame or casting 33 which is secured to the upper front part of the frame 20 by means of angle brackets 34. The frame or casting 33 shown in the drawing is identical with that heretofore employed in the Wahl machine except that some of the lower part of the Wahl casting has been cut away. Journaled in said casting are three wheels or rolls 35, 36 and 37, the last mounted in an overhanging bracket 38 located at the middle of the machine. These wheels are the main supporting and guiding means for a truck or calculator carriage 40 on which any desired number of totalizers 41 can be mounted. This truck is also partly supported at its ends by brackets 42 rigidly mounted on the ends of the typewriter carriage 22 so as to make the truck travel toward the right and left in unison with said carriage. All of these parts, namely, the wheels 35, 36 and 37, the truck 40, totalizers 41 and brackets 42, are as here shown of standard Wahl construction.

The actuator framework, in addition to the casting 33, includes a number of sheet metal plates or brackets mounted on said casting. 43 and 44 are respectively left-hand and right-hand end plates secured to the ends of casting 33 by screws 45. Between these end plates there are two other plates 46 and 47 (Figs. 2, 15 and 4), said plates having feet bent off therefrom and secured by screws 48 to the casting 33. Between the plates 46 and 47 is another plate

50 similarly secured to the casting 33 (Figs. 2 and 14). The upper parts of plates 46, 47, and 50 are or may be similar to those heretofore employed in the Wahl machine. A master wheel 51 is rigid on a shaft 52, the reduced ends of which are journaled in the plates 46 and 47. On this shaft there is mounted a collar 53 integral with a drive gear 54 and having a splined connection 55 with the master wheel shaft. As shown in Figs. 2 and 15, an arbor or shaft 56 is slidably but non-rotatably mounted in plates 46 and 50, and on this arbor a pinion 57 is rotatably mounted between collars so that the pinion moves lengthwise with the arbor but is free to turn on the arbor. In the Wahl machine means are provided for shifting this pinion to the right and left which means may be used in the present machine but is not shown in the present drawings where said shaft is merely shown in Fig. 2 prolonged toward the left and provided on its end with a finger button 58. Any suitable means can be provided for retaining the shaft in its set positions. The shaft 56 is connected with the grooved sleeve 53 by means of a lever of the first order which is a familiar part of the Wahl machine and which I have not here shown. This entire master wheel mechanism, including the drive pinion and change gear mechanism 54, 55, 56, 57, etc., is standard Wahl construction. When the button 58 is pulled toward the left, thus sliding pinion 57 toward the left and pinion 54 toward the right, the machine is set for addition, and when said button is pushed toward the right, reversing the relative adjustments of the two pinions, the machine is set for subtraction.

The machine also includes a master dog 60 mounted on a rock shaft 61 which is pivoted at its ends in plates 47 and 50. This dog includes a locking tooth 62 adapted to engage the teeth of a rack 63 (Fig. 1) to lock the carriage at certain times. This dog also is standard Wahl mechanism both in construction and function. It co-operates with certain levers in the totalizer as is well known. Said levers are at certain times locked against operation by means of a bar 64, Fig. 1, mounted on the frame plates 47, 50 and 46 precisely as in the Wahl machine.

A considerable part of my actuator mechanism is mounted on a main pivot rod or main pivot shaft 65 which, as best shown in Fig. 3, is inserted endwise into the framework passing through suitable holes in the frame plate 43, 46, 47 and 44 so that the rod or shaft is supported both at its ends and also at intermediate points. This rod is maintained in place by flat headed screws 66 screwed into the ends of the shaft and having their heads bearing against the outsides of plates 43 and 44. The shaft can be removed at any time by removing one of these

screws and pulling it out of the machine endwise. The mechanism includes quite a number of movable parts each of which is provided with a hub and said hubs are strung along this pivot rod, some of them having their ends abutting one of the frame plates and others having their ends abutting one another so that the hubs are properly spaced along the rod and any one of them can turn independently thereon. There is one collar 67 which is merely a spacing collar at the right-hand side of the frame plate 47.

The numeral keys 31 have their levers 30 connected by means of pull links 68 with key pieces 70, one for each of the numeral keys including the zero key. Each of these key pieces consists of a three-armed sheet metal lever rigidly mounted on a flanged hub 71 by any suitable means, as for example that which in shops is sometimes called "staking." These key pieces and their hubs are interspersed among the other devices that are strung along the pivot rod 65. By the side of each key piece 70 there is mounted a differential piece 72. In the present instance each of these differential pieces stands just at the right of one of the key pieces 70, and each of them is fastened to a hub 73 journaled on the rod 65. Each of the key pieces 70 has a pin 74 projecting therefrom toward the right into an arc-shaped slot 75 in the associated differential piece 72.

Figs. 4, 5 and 6 show the mechanism connected with the key that writes and adds the digit 9. In the normal position shown in Fig. 4 the pin 74 stands in the rear end of the slot 75 and during the first part of the motion of the key and of the key piece said pin moves in said slot until it reaches the end of the slot after which it carries the differential piece 72 along with the key piece 70 to the end of the stroke. The parts are shown in the middle of the down stroke in Fig. 5 and at the end of the down stroke in Fig. 6. The extent to which the differential piece is moved depends upon the amount of this lost motion which differs with the different keys being least in the case of the 9-key mechanism just referred to.

Figure 16 is a diagrammatic view of the differential pieces 72 as they would be seen from the left if there were no other parts on the shaft 65. It will be seen that the amount of lost motion afforded by the slots 75 is graduated, the 8-key having a little more lost motion than the 9 and so on for the different keys. The last slot 75 whose end is shown in dotted lines in Fig. 16 is that for the zero key where the lost motion is such that the master wheel is not turned at all by that key, although certain other mechanism is operated as will appear.

The differential motion of the various differential pieces 72 is communicated by them to a differential bail which is also mounted

on the rod 65 as shown in Fig. 12. This bail consists of a differential bar 76 supported by arms 77 whose hubs 78 are pivoted on the rod 65 in the same manner as the other hubs, as shown in Fig. 3, in which the left-hand one of said arms and its hub are shown, the right-hand arm being included in the mechanism that is broken away in the figure. The bar 76 appears in cross section in many of the figures and it preferably consists as there shown of a relatively light tube, this being preferable because of its lightness and stiffness. Each of the differential pieces 72 has in the main the outline of a sector but at its rear edge it has a depending lug 80 which normally stands a short distance back of the bar 76, as shown in Figs. 4 and 16, and to this lug there is pivoted at 81 a hook 82 which normally stands in the position shown in Fig. 4, where it is disconnected from the bar 76 but which is capable of being rocked to the position shown in Figs. 5 and 6. Lug 80 moves forward into contact with bar 76 and prong 83 swings down in front of said bar and locks it to the piece 72. In the normal position of the parts the hook 82 is held out of engagement with the bar 76 by reason of its prong 84 coming in contact with a frame bar 85 which rigidly connects the lower parts of the frame plates 43 and 44, to which plates said rod is rigidly secured in any suitable manner as by screws 86, Fig. 1. The hook 82 has its upper edge 87 normally lying across the slot 75 as shown in Fig. 4 and the pin 74 projects across this part of the hook. During the initial lost motion of the pin 74 in the slot 75 said pin positively forces the hook 82 into engagement with the bar 76 as will be understood by reference to Fig. 5, where it will be seen that as long as the pin 74 is in the front part of the slot the hook is positively held in engagement with the bar. The differential bar is thus positively connected or coupled to an operated differential piece.

In order to prevent the hook 82 from becoming disengaged from the bar 76 even during the return stroke of the key, said hook is provided with a tail 88 projecting rearward therefrom and of such shape that during the entire time when the bar 76 is displaced from its normal position said tail is just above the stationary bar 85 and any rocking of the hook about its pivot such as would uncouple it from the bar 76 is prevented until said bar is back in its normal position shown in Fig. 4. The further return movement of the differential piece 72 positively uncouples the hook due to the engagement of the prong 84 with the bar 85.

In order positively to arrest the differential pieces 72 and the differential bar 76 at the end of the stroke, stop devices are provided which may be variously constructed. In the present instance I have shown all

of the differential pieces 72 of the same outline and have provided stationary stepped stops to arrest said differential pieces; and, since the differential bar is at that time 5 positively coupled to the operated differential piece, said bar will of course also be arrested. The form of stop device shown in the present instance includes an angle bar 90 rigidly mounted at the front of the machine 10 on the plates 43 and 44. In the present instance this bar is made of a sufficiently stiff piece of sheet metal and it has ears 91, Fig. 8, bent back from its ends and secured to the frame plates by screws 92.

15 The angle bar 90 has its upper edge bent rearward into a flange 93. The main body of the bar is of such length as to fit snugly between the two end plates 43 and 44 but this flange 93 is prolonged to form two lugs 20 94, Figs. 1, 2 and 17, which enter slots or notches in the end plates 43 and 44 and thus positively prevent any upward or downward slipping of the bar. It will be perceived that this bar can be removed entirely from 25 the machine by merely removing the two screws 92.

20 The flange 93 acts as the final stop for the differential piece 72 for the 9-key as shown in Fig. 6. Due to the lost motion 25 between the remaining differential pieces and their keys, said remaining differential pieces do not move high enough to strike the flange 93 but must be arrested at lower and different elevations. To this end a 30 stepped stop bar 95, a rear view of which is shown in Fig. 17, is secured to the bar 90 by screws 96 and suitably spaced therefrom by washers 97. The lower edge of this bar is made in eight steps 98 at different elevations appropriate to the various numeral keys, the lowest step at the extreme right of Fig. 17 being that for the 1-key. In this machine the zero key is at the right-hand end of the row of keys and its differential piece 72 has only motion enough to take up the lost motion between the lug 80 and the bar 76 without moving said bar. Said differential piece is positively arrested by a stop block 100 seen at the left end of Fig. 17 where it is shown secured to the bar 90 by a screw 101.

35 It will, of course, be understood that the precise detail construction of this series of fixed stops can be varied but the construction shown is simple and rigid and very convenient in the matter of accessibility and detachability. It will be perceived that by the described mechanism the different keys impart different and precisely measured extents of swinging motion to the differential bar 76 which swings about the same pivotal axis as the key pieces and the differential pieces.

40 In order to communicate the motion of the differential bar 76 to the master wheel

51 a segmental rack 102 is provided and journaled on the main pivot rod 65 as best shown in Figs. 2, 3 and 15. A hub 103 pivoted on the rod 65 has a round portion and also a portion having the rectangular 70 outline shown in Fig. 15. The segment 102 is branched, its two arms 104 embracing the rectangular hub 103 to which they are pivoted on a screw 105 so that the segment can be swung about said screw from the 75 inclined position shown in Figs. 2 and 3, where the segment is out of mesh with the pinion 54 or 57 as the case may be, to an upright position where said segment is in mesh. The segment, however, is constrained 80 to turn accurately with the hub 103. An arm 106 is perforated and fastened tightly on the round part of the hub 103 and is further secured to said hub by means of a rivet 107 as shown in Fig. 3, and said arm 85 106 has another hub 108 rigidly secured to the differential bar 76. By the means described the segment 102 partakes precisely of the swinging movements of the differential bar 76. It will be recognized that the 90 construction of this segment 102 and its connection with its hub 103 resemble the corresponding parts of the Wahl machine, but the means for operating the segment is different in the present instance from the 95 Wahl machine.

95 The machine is provided with a universal bar 110 which is operated alike by all of the keys including the zero key. In the present instance this bar is also one member of a 100 full stroke mechanism but other full stroke mechanism can be provided if preferred. Said bar 110 is mounted at the front of the machine a little above the stop bar 90 where it is pivoted to the two end frame plates 105 43 and 44, the manner of such pivoting being best shown in Fig. 12. The bar itself is of such length as to have a working fit between the two end plates and it is pivoted at each end on the reduced inner end 111 110 of a screw 112 screwed through the end plate 43 or 44. The construction is such that by removing these two screws the bar can be slipped out of the machine toward 115 the front. The universal bar 110 in the form here shown consists of a plate or wing of metal, its pivots 111 being near the front edge of said bar, which bar in cross section normally points approximately towards the center of the rod 65, as shown for example 120 in Fig. 14. In order to stiffen the bar near the middle of the machine, the front edge of the bar is rounded concentrically with its pivotal axis, and the frame plate 50 has a depending part shown in Fig. 14 so cut out as partially to embrace the front edge of the bar and to furnish a partial bearing 125 for said bar near the middle of the machine.

130 In order to hold the universal bar in its normal position the devices shown in Fig. 10

are provided. These consist of two dogs 113 and 114 pivoted respectively at 115 and 116 to the frame plate 47 and drawn together by a spring 117 which tends to cause said dogs both to engage opposite sides of a fixed pin 118 projecting from said frame plate 47. The noses of these dogs embrace the universal bar 110 and normally hold it in the middle position described; but said bar can be deflected from that position in either direction, moving the corresponding dog against the tension of said spring 117. The rear edge of the bar 110 is made square and each of the key pieces 70 has a forwardly extending arm with a segmental face concentric with the shaft 65 and containing several notches 120. When a key is depressed this forwardly directed arm moves upward, as indicated in Fig. 10, and swings the universal bar upward against the spring pressure applied to it through the upper dog 113. At the end of the down stroke of the key the key piece moves beyond the range of the universal bar which immediately snaps back to its normal position, as shown in Fig. 6. On the return stroke of the key the universal bar is deflected downward, as shown in Fig. 11. This deflection is also against the tension of the spring 117, which in this instance is applied through the lower dog 113. In both strokes of the key a full stroke is enforced by the square edges of the universal bar entering the notches 120, as will be readily understood. It will be recognized that in principle this universal bar resembles that which has heretofore been in use in the Wahl machine in this sense, namely, that the universal bar normally occupies a middle position, that it is deflected from that position on the down stroke of the key, escapes from the key piece at the end of the down stroke, is deflected in the opposite direction during the upstroke of the key and finally escapes again at the end of the upstroke and returns to its normal middle position.

The connections between the universal bar and the segment 102 will be understood from Figs. 12 and 15. The swinging of the segment to the right and left about its pivot 105 is controlled by a slide 121, the upper rear edge of which is forked to embrace the segment and the reduced ends of which have a limited sliding motion in right and left-hand directions in the frame plates 46 and 50. The lower forward edge of this bar has in it a notch 122 through which passes a cam 123 rigidly mounted on the universal bar 110. This cam consists of a piece of sheet metal stamped out and formed with a foot or base part 124 which is secured to the universal bar 110 by two screws 125. The cam 123 proper is bent up from this base part and is also bent into a sort of S-shape in the same manner as the corresponding cam in

the Wahl machine. The construction is such that the bar 121 and segment 102 normally occupy their right-hand positions shown in Figs. 2 and 12, but when the universal bar is swung upward by the down stroke of a key the sinuous cam 123 forces the bar 121 to the left, swinging the segment into mesh with the pinion 54 or 57. On the return stroke of the key when the universal bar is swung in the opposite direction, this cam positively forces the bar 121 and segment 102 to their extreme right-hand positions. On account of the looseness of the cam 123 in the notch 122, a spring 126 may if preferred be secured to the left-hand face of the frame plate 46 as by means of a screw 127, and this spring may exert a light pressure toward the right on the end of the bar 121.

The universal bar 110 also controls the master dog 60 so as to cause said dog to perform precisely the functions that it does in the Wahl machine. Said dog has a follower roller 128 mounted thereon which runs in a cam groove 130 in a cam plate 131 which is rigidly mounted on an arbor 132 which is pivoted in the frame plates 50 and 47. The cam slot 130 may have the same form as the corresponding cam has heretofore had in the Wahl machine. In order to operate this cam plate it is prolonged toward the front of the machine, its front end having cut therein an open throated cam slot or crotch 133 into which a pin 134 (Figs. 14 and 12) projects from the side of a bracket 135, which bracket is secured by screws 136 to the upper surface of the universal bar 110. The construction is such that when the universal bar is in its normal middle position shown in Fig. 14, the cam plate 131 is held in such a position as to hold the master dog 60 in its normal position; but when the universal bar is swung upward on the down stroke of a key the rear end of the cam plate 131 is swung downward, the follower roller 128 is pushed toward the rear and the dog 60 moves toward the front of the machine and the tooth 62 moves upward into the rack 63 in a manner well known in the art. On the return stroke of the key when the universal bar is swung downward, the cam plate 131 is moved in the opposite direction but the cam slot is of such form that this does not operate the master dog. It will be perceived that the open throated crotch 133 is of such form that the universal bar can be removed from the machine without difficulty due to the engagement of pin 134 with this crotch.

The master wheel 51 (Fig. 14) is normally locked by a dog 137 which enters between two of the teeth of said wheel, said dog being pivoted at 138 on the frame plate 50. This dog has a cam slot 140 therein, which is engaged by a pin 141 projecting leftward from the bracket 135 above de-

scribed, and the shape of this slot is such that when the universal bar is swung upward on the down stroke of a key the dog 137 is withdrawn from the master wheel, 5 but when the universal bar is in normal position and also when it is swung downward on the upstroke of the key, said dog is in engagement with the wheel and is positively locked there by the pin 141 engaging 10 in the slot 140. Said slot is open at its lower end to facilitate removal of the universal bar from the machine. It will be observed that the control both of the master dog 60 and of this locking dog 137 by the universal 15 bar is altogether positive, no springs being used at all except the one which centers the universal bar in its normal position.

It will be understood that other devices 20 may if desired be connected with this same universal bar to perform other functions in the machine. In other words, this bar can be made to perform all necessary functions of a universal bar.

When the differential bar 76 is returned 25 to its normal position it is locked there by means shown in Figs. 8 and 9. The left-hand arm 77 is prolonged upward and shaped with a shoulder 142 which is normally engaged by a matching shoulder on 30 a lock lever 143 which is pivoted at 144 on a bracket 145 projecting forward and thence downward from the casting 33. In the present instance this bracket is made of the same piece of sheet metal as the bracket 46, being 35 bent up from the left-hand end of the foot of said bracket. The latch 143 is prolonged toward the front of the machine so that its forward end overlies the universal bar 110 and when said universal bar is 40 swung upward on the downstroke of a key it lifts the latch and unlocks the differential bar. By this time, however, said bar has become coupled to one of the differential pieces 72 by means of the hook 82. The 45 latch 143 is controlled by a light spring 146, one end of which is connected to said latch and the other end of which may be connected with the arm 77 so as to exert a light pull on the differential frame tending to restore the bar 76 to its normal rear position. Said bar when operated is positively moved 50 back to that position by the hooks 82 and it is positively locked in that position by the latch 143, so that it may be doubted whether 55 this spring action is necessary in ordinary operation, and in any event the tension of the spring may be light. In disconnect position this spring is needed.

It is sometimes desirable for the workman in the shop to be able to free the bar 76 for operation by hand, in order to make certain tests of the totalizer. My actuator may be so constructed as to enable this to be done by imparting a partial down stroke 60 to the zero key. Said key is moved down-

ward far enough to bring the universal bar to the position shown in Fig. 10 where it will prevent the key from returning to normal position and where in the case of any other key than the zero key the bar 76 would be positively coupled to the differential piece. In case it is desired to be able to free the bar 76 by this means the hook 82 may be omitted from the differential piece 72 corresponding to that key. In the 75 present instance, however, this hook is shown in place in Fig. 2 so that when the zero key is operated and the latch 143 is, therefore, unhooked, the bar 76 is positively held in normal position by the hook 82. 80

In order to disconnect the calculating mechanism from the typewriter when doing typewriting that does not involve computing, a disconnect handle 147 is provided. This consists of a lever pivoted at 148 (Figs. 8 and 9) to the bracket 145. The lever is prolonged toward the rear where it is made with two notches 150 which co-operate with a flat spring 151 to retain the handle 147 90 yieldingly in its upper position shown in Fig. 8 where the machine is connected up for operation; or in its lower position shown in Fig. 9 where the calculating mechanism is disconnected. The lever 147 is provided with a knee 152 which when the lever is depressed to the Fig. 9 position forces the universal bar 110 to its extreme depressed position where it is entirely out of the path of the key pieces 70, so that when the numeral keys are operated the universal bar is not 100 moved. In this position of the universal bar the master dog 60 is in its normal position, the master wheel is locked by its dog 137 and the segment 102 is in its right-hand position free of the pins 54 and 57, so 105 that on the operation of any numeral key, whereas the bar 76 will be swung as usual, the master wheel will not be turned and the master dog will not be disturbed.

In order for the mechanism to operate in 110 this manner, however, it is necessary when the calculating mechanism is disconnected that the differential bar 76 be free to swing. To this end the latch 143 has a pin 153 projecting leftward therefrom into the path of 115 the rear arm of the lever 147 so that when said lever is depressed, as shown in Fig. 9, the latch 143 will be elevated to inoperative position.

In order to prevent simultaneous depression of two numeral keys any suitable key arrester or single key mechanism can be provided. In the present instance each of the key pieces 70 has its rear end made in the form of a segment 154 concentric with the shaft 65; and the lower part of this segment normally stands as shown for example in Fig. 4, barely entering a slot 155 cut in the front face of a tube 156 which tube extends lengthwise of the machine, being sup- 120 125 130

ported at its ends by the frame plates 43 and 44. There is one of these transverse slots 155 for each key piece and the construction is such that when any key is depressed its segment 154 moves down through the tube 156 as shown in Figs. 5 and 6. As shown in Fig. 7, said tube contains a series of rods or plungers 158 with rounded ends, which ends come opposite the various slots 155. 5 At each end of the tube 156 there is a fixed plug 160 which is fastened in place by a screw 161 passing through the frame plate and screwed into the plug. These plugs perform the double function of supporting 10 the tube 156 and of limiting the endwise motion of the plungers 158.

The construction is such that the total length of all said plungers is about equal to the length of the tube less the thickness of 15 one of the segments 154, so that when one of said segments is in operated position, as for example the one shown at the bottom of Fig. 7, then these plungers are all crowded together in such a way as to prevent the 20 operation of any other key.

It will be perceived that when one of the differential pieces 72 is positively arrested, as for example the 9-piece is shown arrested in Fig. 6, the key piece 70 and link piece 25 68 are also positively arrested at the same time. It would require a very nice adjustment of the parts to insure that this positive arrest of the key occur at precisely the right instant to cause the type bar 25 to print 30 properly. If said type bar struck the platen too soon it might arrest the key before the calculating operation was quite completed, and on the other hand if said type bar did not strike the platen quite soon enough then 35 the key might be arrested before the type bar had printed. For this reason I have interposed in each train of key connections an elastic connection capable of yielding to a limited extent. The preferred form of 40 this connection is shown in Fig. 13, but the construction can be varied considerably from that shown.

As shown a device 162 is interposed between each numeral key lever 30 and its link 68. In the form shown in the drawing this device includes two branches 163 which embrace the key lever and which are connected by a shouldered pin 164 which passes through a suitable hole in said lever, 50 whereby the device 162 is pivoted to the key lever. Said device is slidably mounted on the link 68 with which it has no positive connection. Said link 68 passes through two holes in said device, one of them being in the upper cap-like part 165 of said device, and the other in a lower disk-like part 166 from which the two arms 163 depend. The parts 165 and 166 are connected by 55 two integral bars 167. A nut 168 lies on the disk 166 and the link 68 is screwed into 60 said nut so that the length of the link can be regulated by screwing it up or down in the nut while disconnected at its upper end from the key piece 70. A spring 170 is coiled about the link 68 and is compressed 70 between the cap 165 and the nut 168, and it is this spring which communicates the motion of the key lever 30 to the link 68. The spring will of course be made of a stiffness suitable for the purpose. Each of 75 the arms 167 is made with a shoulder 171 which limits the relative motion between the device 162 and the link 68; that is to say, the device 162 can move downward with reference to the nut 168 and link 68 against 80 the pressure of the spring 170 only by an amount determined by the distance of the shoulders 171 above the nut 168. There is thus provided a yielding connection which however can yield only to a limited extent. 85 In practice the machine is so adjusted that the differential piece 72 is arrested at the end of its stroke before the type bar has quite reached the platen so that the printing is effected by a further depression of the 90 key lever which results in some compression of the spring 170. The parts are so regulated however that if by any means the master wheel was arrested before it had turned the requisite number of teeth determined by the operated differential piece, then the shoulders 171 would prevent the key 30 from moving so far ahead of the link 68 as to enable the type to print. In other words, a failure of the differential piece to 100 move to its full operated position by a tooth space would prevent the type from printing.

In Fig. 18 I have shown a modification of the yielding connection. According to this modification the link 68 is positively pivoted to the key lever 30 and the key piece 701 partakes of the whole motion of the key. The pin 81 is not mounted on said key piece but is mounted on a separate plate 172 which is pivoted on the rod 65 by the side of the piece 701. The plate 172 has lost motion connection with the key piece 701 consisting of a pin 173 projecting from said plate 172 into a crotch 174 in the key piece, said crotch being wider than the pin. 115 Said key piece and the plate 172 are connected by a stiff spring 175. This spring normally holds the pin 173 at the front end of the crotch 174 and so maintains it during the full operation of the calculating mechanism. At the end of the stroke however the key can move a little further, the distance limited by the width of the crotch 174, against the tension of the spring 175, thus permitting the type bar to print. 120

Attention may be directed to the fact that most of the parts of the differential mechanism all swing about a common center, namely, the rod 65. This makes a means for transmitting power that is very direct 130

and efficient, almost none of the energy being lost in the friction that occurs in transmitting power from a part swinging around one center to a part swinging around another center. It is partly for this reason that the action of my mechanism is very light, offering but slight resistance to the key, and that it may be operated more rapidly than most machines of this character. There are comparatively few parts in the mechanism, and especially there are very few springs. The action of all parts is unusually direct and positive.

Another decided advantage of my mechanism arises from the fact that in case it is desired to remove any one, for example, of the key pieces 70 or the differential pieces 72, it can be done very easily without disturbing other parts of the machine. To this end the mechanic who has to do with these machines can provide himself with a rod of about the same diameter as the rod 65 and he can remove one of the screws 66 and using his extra rod may push it through the machine, thus pushing the rod 65 before it. He can stop this motion at any desired point and by then withdrawing his extra rod can leave a space between the two rods corresponding to the particular hub that he wishes to remove, and this hub will either fall out of the machine or can readily be withdrawn from the machine without disturbing any other. Also in the original assembling of the machine all of these parts that are strung along this rod can be put in place very quickly.

It may also be noted that at the point where the segment 102 acts on the pinions 54 or 57 it is desirable that the shaft 65 not spring away from the pinions so as to render imperfect the meshing of the segment therewith. This action occurs between the frame plates 46 and 47 in which the master wheel shaft and the shaft 56 are journaled. The rod 65 also passes through these same plates so that, at that point it bears a rigid and exact relation to the shafts of the pinions.

Attention has been called to the readiness with which the universal bar can be removed from the machine and replaced in it and it may be added that the bracket 135 fastened on this bar and also the cam 123 are secured to said bar each by two screws which are at the front of the machine and on the upper part of the bar where they are very readily accessible. In case of any injury to or breakage of either of these parts it can therefore be almost instantly removed and very quickly replaced with another.

It will of course be understood that many changes can be made in the details of construction and arrangement without departing from my invention.

What I claim as new and desire to secure by Letters Patent, is,

1. In a calculating machine, the combination with a set of digit keys, of a shaft, a series of key pieces pivoted on said shaft and connected with said keys, a set of differential pieces pivoted on said shaft and each having lost motion connection with one of said key pieces, and a differential bail swinging concentrically with said shaft and operated by said differential pieces.

2. In a calculating machine, the combination with a set of digit keys, of a shaft, a set of key pieces pivoted on said shaft and each connected with one of said keys, a set of differential pieces pivoted on said shaft and each having lost motion connection with one of said key pieces, a differential bail swinging concentrically with said shaft, and means for positively coupling an operated differential piece to said differential bail.

3. In a calculating machine, the combination with a set of digit keys, of a shaft, a set of key pieces pivoted on said shaft and connected with said keys, a set of differential pieces having lost motion connection with said key pieces, a differential bail swinging concentrically with said shaft, a set of coupling devices for coupling the operated differential pieces to said bail, and means operated by each key piece during its lost motion with respect to its differential piece for operating the corresponding coupling device.

4. In a calculating machine, the combination of a digit key, a pivoted key piece connected with said key, a differential piece pivoted by the side of the key piece and having lost motion connection therewith, a differential device operated by said differential piece, a coupling device mounted on said differential piece and means whereby said key piece during its lost motion with respect to said differential piece operates said coupling device to positively couple the differential device and the differential piece together.

5. In a calculating machine, the combination of a digit key, a pivoted key piece connected with said key, a differential piece pivoted by the side of the key piece and having lost motion connection therewith, a differential device operated by said differential piece, a coupling device mounted on said differential piece, means whereby said key piece during its lost motion with respect to said differential piece operates said coupling device to positively couple the differential device and the differential piece together, and means for positively maintaining said coupling device in coupling position during the operation of said digit piece.

6. In a calculating machine, the combination with a set of digit keys, of a shaft, a series of key pieces pivoted on said shaft

- and connected with said keys, a set of differential pieces pivoted on said shaft and each having lost motion connection with one of said key pieces, a differential bail swinging concentrically with said shaft and operated by said differential pieces, and a universal bar operated by said key pieces. 5
7. In a calculating machine, the combination with a set of digit keys, of a shaft, a set of key pieces pivoted on said shaft and each connected with one of said keys, a set of differential pieces pivoted on said shaft and each having lost motion connection with one of said key pieces, a differential bail swinging concentrically with said shaft, means for positively coupling an operated differential piece to said differential bail, and means for positively arresting the operated differential piece. 10
- 20 8. In a calculating machine, the combination with a set of digit keys, of a shaft, a set of key pieces pivoted on said shaft and each connected with one of said keys, a set of differential pieces pivoted on said shaft and each having lost motion connection with one of said key pieces, a differential bail swinging concentrically with said shaft, means for positively coupling an operated differential piece to said differential bail, means for positively arresting the operated differential piece, and means for insuring a full stroke of said key piece. 15
- 35 9. In a calculating machine, the combination of a set of digit keys, a shaft, a set of key pieces pivoted on said shaft and connected with said keys, a differential bail pivoted on said shaft and operated differential distances by said key pieces, a gear segment pivoted on said shaft and connected to swing with said differential bail, a pinion operated by said segment, a universal bar, and means operated by said universal bar for moving said segment into and out of mesh with said pinion. 20
- 40 10. In a calculating machine, the combination of a set of digit keys, a fixed shaft, a set of key pieces connected with said keys, a set of differential pieces each having lost motion connection with one of said key pieces, a differential bail having arms, said key pieces, differential pieces and arms all having hubs strung along said shaft and a frame through which said shaft passes, the construction being such that a rod can be inserted in said frame so as to push said shaft endwise, and said rod and shaft can be separated so as to remove any desired one of said hubs leaving the balance of said hubs in place in the machine. 25
- 45 11. In a calculating machine, the combination of a pivoted key piece, a pivoted differential piece having lost motion connection with said key piece, a differential device operated by said differential piece, and a coupling device for coupling said differential piece and said differential device together, said differential piece having a lug adapted to engage said differential device to move it, and said coupling device preventing overthrow of said differential device relative to said differential piece. 30
- 50 12. In a calculating machine, the combination of a pivoted key piece, a pivoted differential piece having lost motion connection with said key piece, a differential device operated by said differential piece, a coupling device for coupling said differential piece and said differential device together, said differential piece having a lug adapted to engage said differential device to move it, and said coupling devices preventing overthrow of said differential device relative to said differential piece, and a stop for arresting said differential piece. 35
- 55 13. In a calculating machine, the combination of a set of digit keys, a set of digit pieces operated by said keys, a set of differential pieces operated by said digit pieces and having lost motion connection therewith, a differential bar operated by said differential pieces, coupling devices on said differential pieces and normally disengaged from said differential bar, means whereby an operated key piece during said lost motion positively operates said coupling device to couple the differential piece to the differential bar preparatory to operating said differential bar, and a full stroke device acting on said key piece and arranged to prevent backward motion thereof by the time when said coupling device is operated. 40
- 60 14. In a calculating machine, the combination of a set of digit keys, a shaft, a set of key pieces pivoted on said shaft, a set of differential pieces pivoted on said shaft, a differential bail swinging concentrically with said shaft and operated by said differential pieces, and a universal bar pivoted to swing about an axis parallel with said shaft and operated by said key pieces. 45
- 65 15. In a calculating machine, the combination of a set of digit keys, type bars operated by said keys, differential mechanism operated by said keys, a positive stop for arresting said differential mechanism at the end of its stroke, spring connections between said keys and said differential mechanism adapted to yield to an extent sufficient to allow the type bar to print after the differential mechanism has been arrested at the end of its stroke, and means to limit the yielding of said spring connections to an amount insufficient to allow the type bar to print in case the differential mechanism should be arrested after a number of units of movement less than the number appropriate to the operated key. 50
- 70 16. In a calculating machine, the combination of a set of digit keys, a set of differential pieces operated by said keys, a differ- 55
- 75 17. In a calculating machine, the combination of a set of digit keys, a set of differential pieces operated by said keys, a differ- 60
- 80 18. In a calculating machine, the combination of a set of digit keys, a set of differential pieces operated by said keys, a differ- 65
- 85 19. In a calculating machine, the combination of a set of digit keys, a set of differential pieces operated by said keys, a differ- 70
- 90 20. In a calculating machine, the combination of a set of digit keys, a set of differential pieces operated by said keys, a differ- 75
- 95 21. In a calculating machine, the combination of a set of digit keys, a set of differential pieces operated by said keys, a differ- 80
- 100 22. In a calculating machine, the combination of a set of digit keys, a set of differential pieces operated by said keys, a differ- 85
- 105 23. In a calculating machine, the combination of a set of digit keys, a set of differential pieces operated by said keys, a differ- 90
- 110 24. In a calculating machine, the combination of a set of digit keys, a set of differential pieces operated by said keys, a differ- 95
- 115 25. In a calculating machine, the combination of a set of digit keys, a set of differential pieces operated by said keys, a differ- 100
- 120 26. In a calculating machine, the combination of a set of digit keys, a set of differential pieces operated by said keys, a differ- 105
- 125 27. In a calculating machine, the combination of a set of digit keys, a set of differential pieces operated by said keys, a differ- 110
- 130 28. In a calculating machine, the combination of a set of digit keys, a set of differential pieces operated by said keys, a differ- 115

ential bar, means for locking said differential bar in its normal position, means for coupling said differential bar and an operated differential piece together, and means for releasing said normal locking means after said differential bar has become coupled to a differential piece.

17. In a calculating machine, the combination of a differential bar, a latch for engaging said differential bar in normal position, and a universal bar, said latch having a part thereof overlying said universal bar whereby said latch is released when said universal bar is operated.

18. In a calculating machine, the combination of a set of keys, differential mechanism operated by said keys, a universal bar normally adapted to be operated by said keys, and disconnect mechanism including a lever having a shoulder adapted when the lever is operated to engage said universal bar and move it to a position where it cannot be operated by said key.

19. In a calculating machine, the combination of a set of numeral keys, key pieces operated by said keys, and a universal bar for said keys mounted in the machine by two pivots at the ends thereof, said pivots being removable and said universal bar being thereupon removable bodily from the machine.

20. In a combined typewriting and calculating machine, the combination of numeral keys, type bars operated by said keys, differential mechanism operated by said keys, and a connection between each key and said differential mechanism, said connection being yieldable to a definite limited extent whereby the key can move to a limited extent after the differential mechanism has been arrested.

21. In a combined typewriting and calculating machine, the combination of a numeral key, a type bar connected to said key, differential mechanism, a link connected with said differential mechanism, a device connected with said key and slidably con-

nected with said link, a spring connecting said device and said link, and means for limiting the amount of relative motion between said device and said link.

22. In a combined typewriting and calculating machine, the combination of a key, a type bar operated by said key, differential mechanism, a link connected with said differential mechanism, a device slidably mounted on said link, a nut screwed on said link and having a limited motion relative to said device, a spring acting between said device and said nut, and a connection between said device and said key whereby said key operates said differential mechanism but can move against the pressure of said spring after the differential mechanism has completed its motion a distance limited by the relative motion of said nut and said device.

23. In a calculating machine, the combination of a set of numeral keys, a universal bar situated at the front of the actuating mechanism of the calculating machine and readily removable, and actuating brackets mounted on said universal bar in accessible positions and removably secured thereto.

24. In a calculating machine, the combination of a set of digit keys, a set of key pieces operated by said keys, a set of differential pieces each operated by one of said key pieces which latter has lost motion relating to its differential piece, a differential device common to all of said keys, coupling devices each positively coupling an operated differential piece to said differential device, and means for positively arresting each operated differential piece and, through it and said coupling device, arresting said differential device.

Signed at the borough of Manhattan, city of New York, in the county of New York and State of New York, this 14th day of May, A. D. 1921.
